[57] **CLAIM**

The ornamental design for a toy vehicle, substantially as
shown and described.

DESCRIPTION

FIG. 1 is a perspective view of a toy vehicle showing
my new design;

FIG. 2 is a side elevational view thereof, the side oppo-
site being substantially a mirror image thereof;

FIG. 3 is a top plan view thereof;

FIG. 4 is a bottom plan view thereof;

FIG. 5 is a front elevational view thereof;

FIG. 6 is a rear elevational view thereof; and

FIG. 7 is a perspective view of the toy vehicle which is
similar to FIG. 1, but showing the vehicle in a slightly
different condition.

FIG. 2
